DESIGN FOR A TOY GUN

Boyd E. Cousins, Kansas City, Mo.

Application March 3, 1944, Serial No. 112,773

Term of patent 3½ years

(Cl. D34—15)

To all whom it may concern:

Be it known that I, Boyd E. Cousins, a citizen of the United States, residing at Kansas City, in the county of Jackson and State of Missouri, have invented a new, original, and ornamental Design for Toy Gun, of which the following is a specification, reference being had to the accompanying drawing, forming part thereof.

Fig. 1 is a perspective view of a toy gun showing my new design.

Fig. 2 is a front elevation of the toy gun.
Fig. 3 is a side elevation of the toy gun.

Fig. 4 is a plan view of the toy gun.

I claim:

The ornamental design for a toy gun, as shown.

BOYD E. COUSINS.
